UNITED STATES PATENT OFFICE.

HENRY B. NICHOLS, OF PHILADELPHIA, PENNSYLVANIA.

GRINDING-MACHINE.

977,324.

Specification of Letters Patent. Patented Nov. 29, 1910.

Application filed April 5, 1910. Serial No. 553,524.

To all whom it may concern:

Be it known that I, HENRY B. NICHOLS, citizen of the United States, residing at Philadelphia, in the county of Philadelphia and State of Pennsylvania, have invented certain new and useful Improvements in Grinding-Machines, of which the following is a specification, reference being had thereto to the accompanying drawing.

10 My invention relates to grinding machines of the class described in Letters Patent Nos. 807,193, 807,194, 856,721 and 913,543, granted to me December 12, 1905, December 12, 1905, June 11, 1907, and February 23, 1909, 15 and has for its object the provision of means whereby machines of this class may be adapted for grinding hollow forms.

Briefly stated, the characteristic features of my present invention are as follows: A 20 supporting bed carries a head stock and a tail stock, the head stock carrying the grinding shaft and constituting the tool support, while the tail stock carries an outboard bearing for the grinding shaft, and constitutes with its disk or crank shaft the means for definitely determining the figure of the 25 cut. The work is carried on a support intermediate of these two elements, and being hollow the grinding shaft passes through it. 30 Various adjustments and feeds are provided, and in one form of machine I provide especially for an angular feed, so that other forms than cylindrical may be ground, such for example as conical shapes or curves of 35 variable radius.

My invention is illustrated in the accompanying drawings in which—

Figure 1 is a side view of a portion of a machine especially adapted to grinding cylindrical forms, such a form being shown in the figure in section; Fig. 2 is a similar view of a modified machine for grinding large cylinders. Figs. 3, 4 and 5 are respectively a plan, a side elevation, and an end elevation with spindle mechanism removed of a modified form of machine especially adapted for grinding conical forms.

Referring to Fig. 1, A is the head stock or tool support of a machine similar to those in my patents hereinbefore referred to. This head stock is pivotally mounted upon a bed which also carries the tail stock mounting B and the work holder or carriage C. The details of the mounting, as well as the 50 bed of the machine, are not shown in this figure, but are similar to those in the patent.

ents and also to those in Figs. 3, 4 and 5 which will be more fully described hereinafter. The grinding wheel *a* is shown mounted upon a hollow shaft *a'* having end motion in the yoke structure *a²*, being therein connected with feed mechanism fully described in my patents and especially in No. 913,543. In that patent, the tail stock carries a driven disk *F*, which as it rotates 60 swings the tail of the shaft in a circle, gives the yoke mechanism compound motion in its universal bearings and rotates the spindle, while the tool is itself rotated thereon by means of separate drive connections in the 65 yoke. Such a construction is satisfactory for some purposes, but for large forms and especially for long forms, springing and vibration of the spindle become factors, as they tend to affect the cut and render it non-uniform. In the present case therefore, I 70 change the swing stock to the opposite end of the bed plate or frame of the machine, and provide a supplementary spindle *a²⁰* 75 preferably concentric with and passing axially through the driving spindle, and connect the end of this supplementary spindle through a universal joint or movable outboard bearing *b* with the rotating disk *b'* 80 on the stub driving shaft *b²* in the tail stock. 85 The universal joint *b* consists of a ball and socket, in the present case the latter being secured on the disk *b'* with radial adjustment, as in my patent. Longitudinal feed is effected by the carriage C carrying the work, 90 being moved by a feed screw as disclosed in the patent; and cross feed is effected by moving the grinding wheel *a* on the spindle *a'* 95 in a manner also described in the patent.

In the modification shown in Fig. 2, the 95 tool support A, the wheel *a* and the spindle *a'* are the same as in Fig. 1, but instead of the supplementary spindle *a²⁰*, I provide an extended bracket *B'* eccentrically mounted on the disk *b'* on the tail stock B and rotating therewith. At the extremity of this bracket I provide pivoted bearing plates receiving the spindle *a'* and constituting an outboard bearing for the same. This bearing in its entirety is marked *b³*, and may be 105 constructed in any desired or suitable manner. In the form shown the upper plate *b³⁰* is detachable by removal of the usual side bolts, to permit of the disengagement of the spindle and the removal or adjustment of 110 the work or of the parts of the machine.

It may be stated as a guide to the un-

derstanding of the functions of these two cylinder grinders that the cylinder assumed for the machine in Fig. 1 is 36x36 inches internal measurement, while the cylinder assumed in Fig. 2 is 48x60 inches. The form of bearing shown in Fig. 2 I may call a follower bearing for accurate guidance. The longitudinal feed is effected as before by the carriage being moved through the medium of a longitudinal feed screw; and cross feed is effected by moving the grinding wheel and the spindle through the bearing b^3 , by means of the yoke mechanism.

Having thus briefly described the simple forms of machine employing the outboard bearing, I will now pass to Figs. 3, 4 and 5, in which a complete machine is illustrated especially adapted for conical forms. It will be understood by those skilled in the art after reading this description that curved forms of variable radius may also be ground in this machine by providing correspondingly variable feeds. The description will be limited to the conical arrangement however, for the sake of clearness and simplicity.

In the figures mentioned, the head stock, tail stock and carriage are marked A, B and C respectively, as before; all three being supported upon a flanged bed plate D. The head stock A, which has a pedestal with a long base, is fitted directly to one end of the bed. The tail stock B, is secured upon a supplemental column or pedestal with a broad base which is also fitted upon and directly secured to the bed at its opposite end. Between these two the carriage is adapted to be raised and lowered and reciprocated by means of feed screws. These screws are shown at c , c' and c^2 in Fig. 4. The carriage itself consists of two members, that is the carriage proper, marked c^3 , which has vertical end flanges c^4 engaging dovetail slides b^4 and b^5 on the tail stock and head stock respectively; and a superposed work support adapted to slide longitudinally on the member c^3 , and provided with guiding flanges and a drop lug engaging the feed screw c . This work support is marked c^5 , and is provided with the usual transverse T-slots to receive securing bolts of the work cradle E and the binding chain F. The work being conical, or of greater diameter at one end than the other, requires special supports in order to center it properly as shown. The cradle and chain, together with a supplemental cradle E' are employed for this purpose, and are composed of the following instrumentalities: The cradle E comprises a base plate e from which rise the slide supports or horns e' and e^2 , these being curved so as to form substantially an arc of a circle concentric with the main axis of the machine, that is to say the axis passing through and centering both

the tail stock spindle and the head stock universal joint. Radial slides are provided in both the horns, as best shown in Fig. 5, at e^8 and e^4 , to which are fitted slide blocks or adjustable jaws e^5 and e^6 , held in place by bolts e^7 and e^8 , working in slots in the jaws, and adjusted by means of follower screws e^9 and e^{10} . A third slide block may be provided if desired, as indicated at e^{11} , and these three blocks are set up to the contour of the work while leveling and before centering. The cradle E' may have a base and horns similar to those of the larger cradle, and may or may not be fitted with slide blocks according to the nature of the work and the probable amount of variation in its radius.

To hold the work down upon the cradles the chain F is provided with turn buckle f and a strain plate f' bolted to the support c^6 . The turn buckle in the present case is reduced to a simple hook plate with an L-flange to take the nut on the end of the strain bolt. The chain passes up over a saddle f^2 flanged at f^3 and with a hook f^4 at the other end to take over the upper edge of the work.

The grinding is done by the wheel a , rotated by means of the hollow shaft a' which extends back through bearings in the yoke a^2 and terminates at the traveler a^{10} , through one member of which the feed screw a^{11} passes, which is manipulated through bevel gears by the hand wheel a^{12} . Thus the wheel is fed in a line parallel to the surface of the cone it is grinding. The wheel is rotated by a drive pulley through bevel gears and a spline connection, as described in my patents.

In order to steady the wheel, and also to rotate its spindle, so as to describe the circles of a cone, I provide in this case as in the cylinder grinder an outboard bearing in the shape of a universal joint b on the face plate or disk b' of the tail stock spindle. The difference is this, that whereas the feed in the cylinder grinder is attained through reciprocation of the carriage, in the cone grinder it is attained by reciprocating the wheel while maintaining the carriage and the work thereon stationary.

As plainly seen in Figs. 3 and 4, the carriage feed screw c is turned through bevel gears by means of the hand wheel W for purpose of cross feed. The vertical adjustment of the carriage is effected by means of a crank C' which through bevel gears at c^6 and c^7 at opposite ends of the spindle c^8 is capable of turning the longitudinal shaft c^9 engaging worm wheels c^{10} and c^{11} on the jack screws c^1 and c^2 . These screws are located centrally of the carriage, and all side motion is prevented by means of the extended flanges c^4 , engaging the dovetail slides b^4 and b^5 . It will be observed that by thus

directly connecting the carriage (which supports the work) and the head and tail stocks (which determine the alinement of the tool) accurate adjustment is insured for all positions of the tool and carriage.

In my prior Patent No. 913,543, hereinbefore referred to, I have described and claimed automatic caliper means for regulating the cut. The machine illustrated in 10 said patent was intended for grinding hollow forms and especially cylindrical forms. The present machine being essentially an improvement over that one, it is to be understood that the caliper means, and all 15 other features described and illustrated in the said patent may be applied to the present machine and are contemplated herein. For example, it must be evident that the inner surface of the conical form shown in Fig. 4 20 would not be accurately ground if the wheel *a* were suffered to wear away without suitable compensation for the loss in diameter. Such compensation may be produced by moving the carriage *C* through the medium 25 of the hand wheel *W*, but it may also be conveniently produced by automatic calipers in every respect similar to those in the prior patent.

I am aware that a number of variations 30 and modifications may be made in the details of the machine I have described herein, among which are to be noted the provision of automatic feeding means for the carriage to compensate for wear on the wheel, 35 these being regulated if desired by automatic calipers as above mentioned, also the provision of either manual or automatic means for varying the swing of the spindle by varying the rotary distance of the ball 40 and socket joint from the center of the base plate on the tail stock. This latter means would enable curved forms other than cones, that is to say forms varying in diameter at different points in their axes to be accurately 45 cut or ground. It goes without saying that any desired cutting tool may be substituted for the grinding wheel without departing from the scope of the invention. All such changes are contemplated by me, 50 which lie within the scope and purview of the appended claims.

Having thus described my invention, what I claim and desire to secure by Letters Patent is—

55 1. In a grinding machine, the combination with a work support of a tool support, a tool spindle swiveled for universal movement therein, means for adjusting said tool spindle relative to said work, means to rotate said spindle operative in all the angular positions thereof, and means on the same side of said tool support as said work support to impart to said spindle a motion which will give the desired contour to the 60 work.

2. In a grinding machine, the combination with a work support of a tool support, a tool spindle swiveled for universal movement therein, means for adjusting said tool spindle relative to said work, means to rotate said spindle operative in all the angular positions thereof, a driven member carrying an outboard bearing for the tool adapted to impart the desired contour to the work, and means to adjust said work support relatively to said tool support. 70 75

3. In a grinding machine, the combination with the frame thereof, of a work support carried by said frame, a tool support also carried by said frame, a tool spindle 80 mounted therein and means to rotate the same, means for adjusting said tool spindle relative to said work, and driving means, also carried by said frame, and connected to the outer end of the spindle to impart to the 85 latter a shaping motion whereby the desired contour of the work may be produced.

4. In a grinding machine, the combination with the frame thereof, of a work support mounted upon said frame, means for adjusting the work support, a tool support also mounted upon the frame, and a grinding tool carried thereby so as to have universal motion thereon, means for driving said tool so as to impart to it a cutting 95 motion, means for adjusting said tool spindle relative to said work and a driven member carrying an outboard bearing for the spindle to guide the tool to impart the desired contour to the work. 100

5. In a machine of the class described, the combination of a standard, a bearing swiveled thereon for universal movement, a rotary tool spindle journaled in said bearing and carrying an abrading tool, a work support and means for adjusting it toward and away from said standard, a rotatable face plate located on the same side of said standard as said work support, and means carried by said spindle adapted to engage said face plate, whereby said spindle may be caused to carry said tool in a curved path around the work. 105 110

6. In a machine of the class described, the combination of a tool spindle, a tool carried thereon intermediate of its ends, means at one end to rotate the same and means at the other end to simultaneously give it a universal motion about an intermediate point of its axis. 115

7. In a machine of the class described, the combination of a tool spindle, means to give the same a universal motion about an intermediate point of its axis, means located about said intermediate point to rotate said spindle, a cutting or abrading tool carried between said intermediate point and one end of said spindle, and means connected with the same end thereof to swing it about said intermediate point, whereby said tool 120 125 130

may be given an orbital motion and at the same time be rotated, while rigidly supported.

8. In a machine of the class described, the combination of a tool support, a tool carrying member universally swiveled on said support, a tail stock carrying a rotatable face plate with its center coinciding with the center of universal movement of said tool carrying member, a socket member adjustably secured to said face plate and connections between said socket member and the end of said tool carrying member whereby rotation of the face plate will impart a universal swinging movement to said tool carrying member, and will prevent springing or vibration of the same during its travel.

9. In a machine of the class described, a tool support, a spindle journaled thereon so as to have universal motion, means for rotating said spindle, a tool on the spindle, means for reciprocating the spindle, a tail stock and means journaled thereon adapted to swing the spindle, and a carriage between the tool support and tail stock, with means to secure the work thereon.

10. In a machine of the class described, a tail support, a spindle journaled thereon to have universal motion, means for rotating the spindle, means for reciprocating the spindle, a cutting tool carried by the spindle at a point remote from its universal bearing, means for supporting work in position to be acted upon by the tool, and rotary means connected to the spindle on the opposite side of the tool from the tool support adapted to swing the spindle and tool and guide the latter over the surface of the work.

11. In a machine of the class described, a head stock or tool support, a spindle journaled thereon so as to have universal motion, means to rotate said spindle, means to reciprocate the spindle, a tool on the spindle at a point remote from its universal bearing, a work support, and rotary means connected to the end of the spindle adapted to swing the same so as to describe the figure of a cone having its apex at the center of universal motion, whereby the combined rotation and reciprocation of the tool will enable cuts to be made in the figure of a cone.

12. In a machine of the class described, a tool and tool spindle, a work support, means to rotate the spindle and tool, means to reciprocate the tool, and means to swing the spindle and tool in circles of varying diameter, whereby round surfaces of correspondingly varying diameter may be accurately cut.

13. In a machine of the class described, a supporting bed, a pair of pedestals carrying a head stock and a tail stock respectively, dovetails formed on both edges of each of the opposed faces of the pedestals, a hori-

zontal carriage having transverse end brackets with overturned edges forming dovetails to engage and coöperate with the dovetail edges of the slides, a pair of parallel vertical feed screws with their lower ends set in foot-step bearings on the bed and their upper ends in sockets on the lower side of the carriage, a worm wheel on each screw, a shaft carrying worms engaging the said worm wheels, said shaft passing through one of said pedestals, operating means for turning said shaft and thereby imparting motion to the feed screws simultaneously, a work support scored with transverse holding slots and fitted to the upper surface of the carriage so as to slide longitudinally thereon, a drop lug on the lower side of said work support, a longitudinal feed screw journaled at its ends in the end brackets of the carriage, and threaded through said lug, and operating means for said feed screw.

14. In a machine of the class described, a tool support and tool, with means for driving the same, and a work support with means for securing forms of varying diameter thereon comprising a cradle and binding means for holding the form therein.

15. In a machine of the class described, a tool support and tool, with means for driving the same, and a work support with means for securing forms of varying diameter thereon comprising a cradle with adjustable supports, and binding means for holding the form therein.

16. In a machine of the class described, a tool support and tool, with means for driving the same, and a work support with means for securing forms of varying diameter thereon comprising a cradle with adjustable supports, a saddle adapted to fit the upper portion of the form, and binding means passing over the saddle with ends secured to the work support.

17. In a machine of the class described, a tool support and tool, with means for driving the same, and a work support with means for securing forms of varying diameter thereon comprising a cradle with adjustable slide supports, a saddle adapted to fit the upper part of the form, and a binding chain or band passing over the saddle and secured by means of a strain plate or turn buckle to the work support.

18. In a machine of the class described, a bed plate, a pair of pedestals spaced apart thereon, a tool support carrying a tool with driving means therefor, and a swing plate for the tool, slides formed on the opposed faces of the pedestals, a carriage fitted for vertical travel on said slides, a work support consisting of a plate fitted for longitudinal travel on the carriage, a cradle having adjustable horns or slide supports rising from opposite sides of the plate, a binding member

adapted to pass over the work when placed in the cradle, and a strain member securing the binding member to the plate.

19. In a machine of the class described, a bed plate, a pair of pedestals spaced apart thereon, a tool support carrying a tool with driving means therefor, and a swing plate for the tool, slides formed on the opposed faces of the pedestals, a carriage fitted for 10 vertical travel on said slides, a work support consisting of a plate fitted to horizontal slides on the carriage, a pair of cradles se-

cured transversely on said plate, and a binding member adapted to pass over the work when placed in the cradles, with its ends secured to the opposite sides of the plate between the cradles. 15

In testimony whereof I affix my signature in presence of two witnesses.

HENRY B. NICHOLS.
